US0D1081313S

(12) **United States Design Patent** (10) **Patent No.:** **US D1,081,313 S**
(45) **Date of Patent:** **** Jul. 1, 2025**

(54) **EXTRACTOR INSERT**

(71) Applicant: **Apex Brands, Inc.**, Apex, NC (US)

(72) Inventors: **Zhihong Fu**, Cary, NC (US); **Jesse Higgins**, Raleigh, NC (US); **Sujith Sunny**, Pune (IN)

(73) Assignee: **APEX BRANDS, INC.**, Apex, NC (US)

(**) Term: **15 Years**

(21) Appl. No.: **29/854,126**

(22) Filed: **Sep. 22, 2022**

(51) **LOC (15) Cl.** **08-05**

(52) **U.S. Cl.**

USPC **D8/29**

(58) **Field of Classification Search**

USPC D8/21, 29, 70, 397

CPC B25B 13/065; B25B 13/50; B25B 27/0042

(57) **CLAIM**

The ornamental design for an extractor insert, as shown and described.

DESCRIPTION

FIG. 1 is a perspective top view of an extractor insert in accordance with an embodiment of the present invention; FIG. 2 is a top view of the extractor insert of FIG. 1; FIG. 3 is a left side view of the extractor insert of FIG. 1; FIG. 4 is a front view of the extractor insert of FIG. 1; FIG. 5 is a right side view of the extractor insert of FIG. 1; FIG. 6 is a rear view of the extractor insert of FIG. 1; FIG. 7 is a bottom view of the extractor insert of FIG. 1; and, FIG. 8 is a perspective bottom view of the extractor insert of FIG. 1.

The broken lines of the extractor insert in FIGS. 1-8 are illustrative of portions of the extractor insert that form no part of the claimed design.

1 Claim, 8 Drawing Sheets
